United States Patent Office.

OWEN REDMOND, OF ROCHESTER, NEW YORK.

Design No. 2,703, dated July 9, 1867.

DESIGN FOR THE BACK PIECE OF A STAVE MACHINE.

The Schedule referred to in these Letters Patent and making part of the same.

TO ALL WHOM IT MAY CONCERN:

Be it known that I, OWEN REDMOND, of Rochester, Monroe county, and State of New York, have originated and designed a new Pattern for the Guide-Piece or Back of Stave Machines, of which the following is a full, clear, and exact description, reference being had to the accompanying drawings, making part of this specification.

Figure 1 is a perspective view of a stave machine.

Figure 2 is a figure of the back-piece of same detached from the machine.

And it consists in appearance, as nearly as I can describe it, as if several sections, *b b b b b b*, cut from a hollow ring, were attached side to side to produce a given length. A rib, A, is formed on the convex side of the sections, the whole making a new and original design for the back of the stave machine.

What I claim as my invention, and desire to secure by Letters Patent, is—

The design or pattern for the guide or back-piece of stave machines, as herein set forth.

OWEN REDMOND.

Witnesses:

EDMOND REDMOND,
E. REDMOND.
